UNITED STATES PATENT OFFICE.

MENDEL OBNEY, OF BRILLIANT, OHIO.

SWITCH.

SPECIFICATION forming part of Letters Patent No. 730,041, dated June 2, 1903.

Application filed January 7, 1903. Serial No. 138,145. (No model.)

To all whom it may concern:

Be it known that I, MENDEL OBNEY, a citizen of the United States of America, residing at Brilliant, in the county of Jefferson and 5 State of Ohio, have invented certain new and useful Improvements in Switches, of which the following is a specification, reference being had therein to the accompanying drawings.

10 This invention relates to certain new and useful improvements in switches, and the invention is particularly adapted for use in connection with street-railway switches, and has for its object to provide novel means 15 whereby a switch-point can be readily manipulated from the car, so as to permit the car to pass on the main track or side track, as desired.

Briefly described, the invention comprises 20 in connection with a pair of pivoted switch-tongues a mechanism comprising throwing-levers arranged in the road-bed and connected to strips extending upwardly adjacent to the rails, whereby they may be engaged by a 25 suitable mechanism supported from the car.

In describing the invention in detail reference is had to the accompanying drawings, forming a part of this specification, and wherein like numerals of reference indicate 30 like parts throughout the several views, in which—

Figure 1 is a top plan view of my improved switch. Fig. 2 is a top plan view of the same, with the cover-plate and rails removed. Fig. 35 3 is a transverse vertical sectional view on line 11 of Fig. 2. Fig. 4 is a detail perspective view of a part of the switch mechanism. Fig. 5 is an underneath plan view of the car-truck, showing the means for operating the 40 trips. Fig. 6 is a side elevation of the same.

In the accompanying drawings, 12 indicate the main rails of the track, 34 the rails of the side track, and 56 the two pivoted switch-tongues. The rails of the track at the switch 45 are supported on cross-ties 7, which rest on sleepers 8, these cross-ties also forming a support for the central cover-plate 9 and for the outside cover-plates 10 11 12. The cover-plate 9 is provided with slots 14, through 50 which extend the pins 15, which connect the switch-tongues 56 to links 16 17, pivoted together at their one end by the pin 18, which

also pivots thereto the one arm of the bell-crank 19. This bell-crank is pivoted to the cross-piece 20 and has its other arm or leg 55 pivoted to the throwing-rods 21 22, which are pivoted together by the same pin which pivots the bell-crank thereto. The throwing-rod 21 is pivotally connected at its outer end to one arm or leg of the bell-crank 23, pivotally supported on the cross-piece 24, with its other arm or leg pivotally attached centrally to the laterally-movable bar 25. The rod 22 is pivotally connected at its outer end to one arm of the three-armed lever 26, pivotally connected 60 to the cross-bar 26' and which has its one arm pivotally connected to the laterally-movable bar 27 and another of its arms pivotally connected to the lever 28. The laterally-movable bar 25 and laterally-movable 70 bar 27 are connected at their ends to the lower end of one arm of the bell-cranks 29, which are pivotally mounted in the sleepers 8. The free ends of the bell-cranks, to which the bar 27 is attached, extend into the 75 slotted shanks 30 of the tripping-pins 31 32, which operate in vertical openings provided therefor in the sleepers 8 and are limited in their upward movement by transverse pins 33, passing through the slotted shanks 30, 80 near the lower ends thereof. The bell-cranks 29 of the bar 25 have their free ends extending into the slotted shanks of the trip-pins 34 35, these trip-pins being of the same construction as the trip-pins 31 32 and shown 85 clearly in detail in Fig. 4 of the drawings. The outer end of the laterally-movable lever 28 is connected to the bell-crank of the same construction as those heretofore described, and it engages in the slotted shank 90 of the trip-pin 36. These trip-pins all operate through suitable openings provided therefor in the cover-plates 10, 11, and 12, and these cover-plates are provided with bosses 95 37, placed outside of the trip-pins, so as to form guideways 38, into which the operating-shoe will engage to depress the respective trip-pins. The switch is operated by mechanism suspended from the car, the preferable form of which is shown in Figs 5, 6 of the 100 drawings, in which 39 indicates the truck-frame, to which is attached the substantially U-shaped bracket 40. Journaled in bearings 41 and extending through the bracket 40 is

the shaft 42, which carries a pin 43, adapted to engage with the pin 44, carried in the vertical shaft 45, extending through the lower bar of the bracket 40 and having a spring 46 arranged thereon between the said lower bar of the bracket 40 and the pin 44. This shaft 45 carries a shoe on its lower end, which is preferably in the form of a wheel 47, as shown. The pin 48 extends through the shaft 42, and connected to this pin on opposite sides of the shaft 42 are cables 49 50, extending to opposite ends of the car and connected to drums 51, which are operative to wind the cable thereon and depress the shoe 47 by means of horizontal levers 52, connected to the shaft of the drums 51, and vertical levers 53, extending through the platform or frame 39. This operating mechanism, it will be observed, can be mounted at either side of the car, and by the provision of the trips 31, 32, 34, 35, and 26 the switch may be thrown in any desired direction irrespective of which side of the car the operating means is mounted—as, for instance, when the car is passing toward the right and the operating mechanism is on the left-hand side of the car the switch will be moved so as to open the side line, while when the trip-operating means is on the right the switch will move to the left and open the main line.

It is to be noted that the shoe 47 is forced downwardly by depressing lever 53, causing either the cord 49 or 50 to be wound on its drum, the shaft 42 rotated so as to cause the pin 43 to engage pin 44 and depress shaft 45 and shoe 47, and cause the latter to engage with the trip so as to depress the latter and actuate the bell-crank and through the connections therewith shift the switch-tongues 5 6 in the desired direction.

It will be noted that various changes may be made in the details of construction without departing from the general spirit of my invention.

Having fully described my invention, what I claim as new, and desire to secure by Letters Patent, is—

1. In a switch, the combination of sleepers,

cross-ties mounted on said sleepers, rails mounted on said cross-ties, a pair of pivoted 50 switch-tongues, a pair of links pivoted together and to which said switch-tongues are connected, a bell-crank pivoted to said links, throwing-rods pivoted to said bell-crank, laterally-movable bars pivotally connected to 55 said throwing-rods, vertically-movable trips mounted in the sleepers, bell-cranks engaging said trips with one arm pivoted to the laterally-movable bars, and means for depressing said trips to actuate the switch-tongues, substantially as described.

2. In a switch, the combination with the pivoted switch-tongues, of a pair of links pivoted to said switch-tongues and pivoted together, a bell-crank pivoted to said links, 65 throwing-rods pivotally connected to said bell-crank, laterally-movable bars, bell-cranks pivotally connecting said bars to the throwing-rods, vertically-movable trip-pins, bell-cranks engaging in said pins and pivotally connected to the laterally-movable bars, and means for depressing the trip-pins to 70 actuate the switch-tongues, in unison, substantially as described.

3. In a switch, a pair of sleepers, cross-ties 75 mounted in said sleepers, rails mounted on said cross-ties, cover-plates mounted on said ties, a pair of pivoted switch-tongues, links pivotally connected together and pivoted to said switch-tongues, a pair of throwing-rods 80 pivotally connected to said links, laterally-movable bars pivotally connected to the outer ends of said throwing-rods, trip-pins mounted for vertical movement in the sleepers, bell-cranks engaging in said trip-pins, and pivotally connected to the materially movable bars, and means for depressing the trip-pins to 85 operate the switch-tongues substantially as described.

In testimony whereof I affix my signature 90 in the presence of two witnesses.
